PAPER-BEAD WINDER

Helen L. Piecuch, Box 158, Epping, N.H. 03042

Filed June 23, 1975, Ser. No. 590,918

Term of patent 14 years

Int. Cl. D8—05

U.S. Cl. D8—222

Fig. 1.

Fig. 2.

Fig. 3.

FIG. 1 is a perspective view of a paper-bead winder showing my new design;

FIG. 2 is a rear elevational view; and

FIG. 3 is a right side elevational view thereof.

I claim:

The ornamental design for a paper-bead winder, as shown.
